UNITED STATES PATENT OFFICE.

OSCAR A. C. OEHMLER, OF WASHINGTON, DISTRICT OF COLUMBIA, ASSIGNOR
OF ONE-THIRD TO WILLIAM FREDERICK GUDE AND ADOLPHUS GUDE,
OF WASHINGTON, DISTRICT OF COLUMBIA.

LIFE-SAVING APPARATUS FOR SUBMARINE BOATS.

No. 857,193.

Specification of Letters Patent.

Patented June 18, 1907.

Application filed February 4, 1907. Serial No. 365,677.

To all whom it may concern:

Be it known that I, OSCAR A. C. OEHMLER, a citizen of the United States, residing at Washington, in the District of Columbia, have invented certain new and useful Improvements in Life-Saving Apparatus for Submarine Boats, of which the following is a specification.

This invention relates broadly to marine life saving apparatus and is designed particularly for use in connection with submarine boats of the type which is now commonly in use.

As is well known, the operation of submarine vessels is exceedingly dangerous, particularly with reference to movement of the boats when submerged, owing to the fact that it is not infrequent that the operating mechanism thereof becomes disabled or partially disabled making it at times difficult, and in some instances impossible, to raise the vessel to the surface of the water.

The present invention has been devised with a view to the above state of affairs especially, embodying improvements in that type of apparatus, the aim of which is to prevent likelihood of disasters such as have happened in the past, caused by failure of the operating mechanism of submarine vessels to work properly and raise the vessel to the surface of the water, whereby the lives of the occupants of the vessels have been lost.

In carrying out the invention, means are provided for not only supplying air and sustenance to the inmates or occupants of a disabled submerged vessel, but effective means is also provided for signaling vessels on the high seas when the submarine boat is submerged and disabled, and its occupants are in distress.

The invention comprises an organization of co-operating mechanisms and parts, the details of which will appear more fully hereinafter, and finally claimed.

For a full understanding of the invention and the merits thereof and also to acquire a knowledge of the details of construction of the means for effecting the result, reference is to be had to the following description and accompanying drawings in which:

Figure 1 is a side elevation showing a submarine vessel submerged, and the apparatus

embodimenting the invention applied thereto and illustrated as in operative position. Fig. 2 is a horizontal sectional view bringing out more clearly the construction of the casing or a well at the upper portion of the boat or vessel, and in which the buoy is housed, adjacent parts of the operating mechanism being also shown. Fig. 3 is a vertical sectional view of the parts shown in Fig. 2. Fig. 4 is a detail vertical sectional view taken about on the line 4—4 of Fig. 3. Fig. 5 is a top plan view, partially broken away, of the upper portion of the buoy. Fig. 6 is an enlarged vertical sectional view, partially broken away bringing out more clearly the detail construction of the upper portion of the buoy. Fig. 7 is a detail cross section of the cable connecting the buoy with the boat.

Corresponding and like parts are referred to in the following description and indicated in all the views of the drawings by the same reference characters.

Specifically describing this invention the numeral 1 indicates a submarine boat of conventional type, the same being propelled in the customary way, and having the usual mechanism for effecting submergence of the vessel and raising it to the surface of the water whenever desired. As the general construction of the submarine boat is immaterial within contemplation of this invention, the same will not be specifically described.

At a suitable point intermediate of the opposite ends of the boat 1, is located a casing or well 2 which projects downwardly from the deck 3 of the boat and which may be of any suitable form, being illustrated as square in the drawings. The casing or well 2 is of a size well adapted to receive a buoy 4 which latter is normally contained by the casing when the apparatus which comprises this invention is not in use. The buoy 4 may be of any suitable type and is preferably hollow, as usual, and adapted to readily move to the surface of the water when released from the casing 2, while the boat 1 is submerged. The construction of the buoy 4 is peculiar however, in certain details, as will be pointed out hereinafter.

The casing 2 is designed to be air and water tight so that when the buoy 4 and con-

nected parts are not in use, they will be effectively housed and prevented from damage by the elements. Applied to the deck 3 and surrounding the opening formed by the upper end of the casing or well 2 is a frame 5 in the upper surface of which is received a packing gasket 6 of suitable material against which the cover or lid 7 of the casing 2 is adapted to seat, when the cover is closed and 10 in its normal position.

The buoy 4 is connected permanently with the boat 1 and for this purpose a cable 8 is provided, the upper end of said cable being attached to a vertical pipe 9 leading through 15 the buoy 4 and the lower end of the cable being secured as at 10 to the bottom 11 of the casing or well 2. The cable 8 is of any suitable material and contains preferably at least two tubes 12-13. The tube 12 is designed 20 primarily as means for supplying air to the occupants of the boat, said tube communicating at the upper extremity with an air passage 14 provided in a head 15 which is attached to the upper tapering portion of the 25 buoy 4. Normally the outermost end of the passage 14 is closed by a friction tight plug 16. The lower end of the tube 12 passes through the bottom of the casing 2 at the point adjacent to which the lower extremity 30 of the cable 8 is secured, and indicated at 10. A suitable air pump, not shown, is connected with the portion of the tube 12 extending 35 downwardly from the bottom 11 of the casing 2 and said pump may be utilized to draw air into the vessel or to force air into the tube 12 whereby to discharge the plug 16 from the passage, after the buoy 4 has arisen to the surface of the water, in the operation of the life saving apparatus. Passage of air into 40 the tube 12, and the supply of air from said tube is controlled by a suitable valve 17. If desired, the tube 12 may be also used to permit rescuers at the surface of the water to supply liquid food or other means of sustenance 45 to the occupants of the submerged boat, should such means of succor be necessary. The tube 13, which also passes through the cable 8, connects at its upper end with a passage 18 formed in the head 15 50 of the buoy 4, said passage 18 being similar to the passage 14 and having its upper outer end extending in an opposite direction, a friction held plug 19 is likewise located so as to normally close the outer end of the passage 55 18.

The tube 13 is utilized, preferably, to permit discharge of a chemical from a suitable tank or receptacle, not shown, and located 60 within the boat, from the upper end portion 60 of the buoy 4 when the latter has been released from the boat and is at the surface of the water. The chemical above mentioned is of such a nature as to immediately ignite when it is discharging from the passage 18 65 and comes into contact with the surface of

the water. This chemical igniting means is similar to that which is commonly employed on vessels for signaling purposes and it will be readily apparent that on discharge of the chemical from the passage 18, and contact thereof with the water, said chemical will burst into a flame forming an effective illuminating signal which may be seen for miles. 70

The construction of the buoy 4 is especially advantageous with a view particularly to its co-operation with the signaling means employed. The upper surface of said buoy, upon the sides adjacent to the head 15, and which surface slants upwardly toward the head 15, is highly polished and formed so as to 80 constitute a reflector. Thus the illuminating signal established by contact of the chemical above mentioned, with the water, will be greatly increased in effectiveness by reason of the fact that the surface at the tapering 85 top portion of the buoy, designated at 20 in the drawings, performs the function of a reflector in the manner above set forth.

Applied to the bottom 11, of the casing or well 2 is a hand pump 21 which is connected 90 with the lower end of the tube 13 and also with a pipe 22 which leads to the chemical tank and said pump 21 is operated in discharging the chemical through the tube 13 upon the surface of the water. 95

The cable 8 is of course of a suitable length to readily admit of the buoy 4 rising to the surface of the water, when the boat 1 is submerged at an ordinary depth and said cable not only contains the tubes 12-13 but also 100 contains suitable wires forming elements of electrical means of establishing communication between the occupants of the vessel and rescuers at the surface of the water as well as for supplying current for power, 105 illuminating, or similar purposes, to apparatus or mechanism within the boat.

Fig. 7 shows an arrangement of the circuit wires applied to the cable 8. The wires 23, for instance, are connected with binding posts 24 projecting upwardly from the head 15 of the buoy and these wires establish suitable connection with a telephone 25 arranged in the boat 1, and shown applied to a side of the casing 2. Similar wires 26 pass from the 115 cable 8 through the bottom of the well, as shown at 27 and these wires may be connected up with electrically driven motor mechanism, or power mechanism of any kind, or may be connected with the circuit wires of an 120 electric lighting system. A cap 29 is attached to the top of the head 15, packing 30 being interposed between said parts. The cap 29 houses the posts 24 and other binding posts 24^a which connect with the upper ends 125 of the wires 26. Rescuers reaching the buoy may readily detach the cap 29 and by connecting suitable wires with the wires 23-26, 130 have telephonic communication with the occupants in the vessel, or supply electrical

power for the purpose hereinbefore set forth. Suitable binding nuts are applied to the posts 24 and 24^a.

It is obvious that when the boat 1 is submerged, its operating mechanism disabled, and its occupants in distress, it is necessary, in making use of the apparatus constituting this invention, to release the buoy 4 and permit the latter with its connecting cable to float upwardly to the surface of the water. To accomplish the above, the cover or lid 7 of the casing 2 must be opened. By reason of the enormous pressure which is exerted upon every square inch of the exposed portions of a submerged boat it will be obvious that peculiar operating mechanism is necessary in order to move a part, such as the cover or the lid 7, preliminary to releasing the buoy 4. The present invention involves a broad principle, in order to facilitate the operation of releasing the buoy 4, of equalizing the pressure of the water on the upper and lower sides of the cover 7 of the well 2. For this purpose a pipe 31 is provided, said pipe leading from a small opening 32 in the deck 3 of the boat, to a small opening in a side of the casing 2. The pipe 31 is designed to control the admission of water to the interior of the casing 2, previous to the operation of releasing the buoy 4, in extremity. A valve 32 is located in the length of the pipe 31 and by opening said valve water will be admitted very quickly to the casing or the well 2 and pressure upon opposite sides of the cover 7 will be equalized. Said cover will thus not have to be opened or raised against the enormous pressure of the water which would be impracticable, it is believed, under ordinary conditions. When water has been admitted to the casing 2 and the water pressure on the cover or lid 7 equalized initial movement is imparted to the cover or lid by a suitable jack device preferably consisting of a vertical screw 33 swiveled in a bracket 34 attached to a side of the casing 2 within the boat. The screw 33 is operable by ratchet lever 35 connected with the screw at the lower end of the latter. The screw 33 passes through openings in the deck 3 and the frame 5 and has threaded connection with the outer or free end of the cover 7. Said screw 33 and its operating mechanisms are designed to impart slight initial movement to the cover 7, and this mechanism is used as it is very powerful and will readily effect the desired movement of the cover though the latter may have been shut for a long period of time.

After the screw 33 has been operated as above described, the main operating mechanism for the cover 7 is actuated. Said main operating mechanism comprises spaced lifting bars 36 the upper ends of which are pivoted to the cover 7 and the lower ends of which have pivotal connection, as shown at

37, with blocks 38, which are adapted to slide in horizontal guides 39 located at opposite sides of the casing or well 2. The blocks 38 as well as the bars 36 are separated from the interior of the casing or well 2 by the walls of 70 the casing, as shown most clearly in Fig. 4 of the drawing, the guides 39 being formed by housing plates 40 attached to the casing 2 at opposite sides of the latter. In order to effect longitudinal movement of the blocks 38 75 relative to the guides 39, screws 41 are provided, said screws being arranged to pass through threaded openings in blocks 38, and in the operation thereof to move said blocks and actuate the lifting bars 36 to raise the cover 80 7. One end of each of the screws 41, one of which is provided for each block 38, passes through a stuffing box at one side of the casing 2 and the projecting extremity of the screw has a suitable bevel pinion 42 secured 85 thereto. The bevel pinions 42 mesh with similar pinions 43 on the opposite ends of a transverse shaft 44 the latter being mounted in brackets 45 extending from the casing 2. A hand wheel 46 secured to the shaft 44 between the ends of the latter may be operated by the occupants of the boat to actuate the screws 41 and the blocks 38, whereby to force the lifting bars 36 vertically and thus elevate the cover 7 to open the latter. The 90 lifting bars 36 have the openings at the lower ends thereof which receive the pivots securing said bars to the blocks 38, slightly elongated to permit the cover 7 to be given the slight initial movement by the screw 33 95 previous to the operation of the main screws 41.

Briefly describing the operation of the invention, should the submarine boat to which the invention is applied be submerged and its operating mechanism disabled, the occupants of the vessel will first open the valve 32^a and permit water to flow into the space in the casing 2 beneath the cover 7. The casing 2 having become filled with water 100 pressure is equalized on opposite sides of the cover 7 and the jacket screw 33 will be actuated to unseat the cover 7 giving it slight initial opening movement. This done, the hand wheel 46 will be turned and the lifting 105 bars 36 actuated to raise the cover 7 into the position shown by dotted lines in Fig. 3. The opening of the cover 7 will release the buoy 4 which is free to move upward to the surface of the water. As a simple means for 110 indicating when the buoy has reached the surface of the water, a galvanometer 48 is situated in the boat 1 convenient for reference thereto by the occupants of the vessel and said appliance is connected by suitable 115 circuit wires in the cable 8 with spaced contacts 49 at the top of the buoy 4. Normally the electric circuit in which the galvanometer 48 is included is broken by the arrangement 120 of the spaced contacts 49. When water is 125

admitted to the casing or well 2, however, the circuit including the galvanometer will be closed as the current will be adapted to pass through the water so as to electrically connect the contacts 49. Closing of the circuit will operate to deflect the needle of the galvanometer in the customary way and the occupants of the boat may readily tell when the buoy 4 reaches the surface of the water, for the reason that as soon as the top of the buoy with the contacts 49 extend above the water the circuit including the galvanometer will be broken and the needle of the latter will be restored to its normal position. As soon as the buoy 4 reaches the top of the water the pump 21 may be operated to discharge the illuminating chemical from the passage 18 and as soon as the chemical comes into contact with the water an illuminating signal will be constituted by the flame bursting forth, and the illumination will be increased by the reflector 20. The signal, may be seen for miles around the buoy and if there are any vessels in sight of the signal succor will be promptly at hand. Removal of the cap 29 will readily admit of connecting suitable wires with the posts 24—24^a to establish electrical connection with the wires 23—26. It will be understood, however, that as soon as the buoy reaches the surface of the water the pump connected with the tube 12 will be operated so as to eject the plug 16 from the passage 14 whereby air may be drawn into the boat through the tube 12 or the tube may be employed in the other ways hereinbefore set forth. The initial operation of the pump 21, preliminary to discharging the chemical from the passage 18, will have expelled the plug 19 in a manner readily apparent. In view of the fact that the casing or well 2 projects inwardly from the deck 3 of the boat, the same does not constitute a projection or abutment extending from the boat and likely to come into contact with objects in the water or be otherwise disadvantageous for reasons which will be readily appreciated.

Having thus described the invention what is claimed as new is:

50. 1. In life saving apparatus for submarine boats, the combination of a boat, a casing applied thereto, a buoy permanently connected with the boat and received in the casing, a cover for the casing, an operating mechanism comprising lifting bars connected with the cover, screws connected with said lifting bars to actuate the same and open the cover, and means arranged exterior to the casing and within the boat for operating the screws as specified.

65. 2. In life saving apparatus for submarine boats, the combination of a boat, a casing applied thereto, a buoy permanently connected with the boat, and received in the casing, a cover for the casing, an operating mechanism

comprising lifting bars pivotally connected at the upper ends thereof with the cover, blocks slidably mounted on the casing and connected with the lower ends of the lifting bars, screws connected with the blocks to impart longitudinal movement thereto, and means exterior to the casing and within the boat operably connected with the screws for simultaneous actuation thereof.

3. In life saving apparatus for submarine boats, the combination of a boat, a casing applied thereto, a buoy received in said casing and housed thereby, a cover for the casing, means for initially operating the cover to unseat the same, and main operating means for opening the cover after actuation thereof by the initial operating means aforesaid.

4. In life saving apparatus for submarine boats, the combination of a boat, a casing thereon, a buoy received in said casing, a cover having a water tight connection with the boat and co-operating with the casing to inclose the buoy, means for initially operating the cover to unseat the same preparatory to opening movement thereof, main operating means for actuating the cover after unseating thereof, and means for supplying water to the space within the casing previous to moving the cover, whereby to equalize pressure at opposite sides of said cover.

5. In life saving apparatus for submarine boats, the combination of a boat, a casing thereon, a buoy received in said casing, a cover having a water tight connection with the boat and co-operating with the casing to inclose the buoy, means for initially operating the cover to unseat the same preparatory to opening movement thereof, main operating means for actuating the cover after unseating thereof, and means for loosely connecting the main operating means with the cover to permit of the initial movement of the cover independent of the main operating means aforesaid.

6. In life saving apparatus for submarine boats, the combination of a boat, a casing applied thereto, a buoy received in said casing, a cover for the casing co-operating therewith, to house the buoy, a rotatably mounted screw having threaded connection with the cover for initial movement thereof, means for actuating the screw, and main operating mechanism connected with the cover to open the same after operation of the screw aforesaid, whereby the buoy may be released from the boat.

7. In a life saving apparatus for submarine boats, the combination of a boat, a casing applied thereto, a buoy received in said casing, a cover or lid for the casing, and auxiliary mechanisms for operating said cover or lid to open the same and release the buoy.

8. In a life saving apparatus for submarine boats, the combination of a boat, a casing applied thereto, a buoy received in said casing,

a cover or lid for the casing, auxiliary mechanisms for operating said cover or lid to open the same and release the buoy, one of the above mechanisms comprising spaced lifting bars connected at the upper ends thereof to the cover, horizontally sliding blocks connected with said lifting bars, screws mounted on the casing and connected with said blocks, and an operating shaft connected with said screws to effect simultaneous operation of the same.

9. In life saving apparatus for submarine boats, the combination of a submarine boat, a buoy, means connecting said buoy with the boat, and permitting the buoy to rise to the surface of the water when the boat is submerged, said buoy embodying a reflecting surface, and means for discharging a chemical illuminating signal from the buoy after it has risen to the surface.

10. In life saving apparatus for submarine boats, the combination of a submarine boat, a buoy connected therewith, means normally preventing separation of the buoy from the boat, means connecting the buoy with the boat and permitting the same to rise to the surface of the water when the boat is submerged, and means for indicating when the buoy reaches the surface of the water on release thereof.

11. In life saving apparatus for submarine

boats, the combination of a submarine boat, a buoy connected therewith, means normally preventing separation of the buoy from the boat, means connecting the buoy with the boat and permitting the same to rise to the surface of the water when the boat is submerged, and an electrically operating means arranged within the boat for indicating to the occupants thereof when the buoy reaches the surface of the water on release of the same from the boat.

12. In life saving apparatus for submarine boats, the combination of a submarine boat, a buoy, a cable connecting the buoy to the boat, means normally preventing separation of the buoy from the boat, means for releasing the buoy, an air passage leading from within the boat through the buoy and the connecting cable thereof, means inserted within the upper end of the passage to normally close the same and means for forcing air through said air passage after the buoy has reached the surface of the water to clear or open the passage to the atmosphere.

In testimony whereof I affix my signature in presence of two witnesses:

OSCAR A. C. OEHMLER.
